United States Patent Office

Des. 207,921
Patented June 13, 1967

207,921

BOTTLE

Alfred D. Sterges, Los Angeles, Calif., assignor to Purex Corporation, Ltd., Lakewood, Calif., a corporation of California

Filed Oct. 6, 1966, Ser. No. 4,180

Term of patent 14 years

(Cl. D58—6)

FIG. 1.

FIG. 2.

FIG. 3.

FIG. 4.

FIG. 1 is a front elevation view of a bottle embodying my new design;

FIG. 2 is a side elevation thereof;

FIG. 3 is a plan view thereof; and

FIG. 4 is a bottom plan view thereof.

The dominant features of my design reside in the portions shown in full lines.

I claim:

The ornamental design for a bottle, as shown and described.
